OIL CUP

Filed Feb. 10, 1926

FIG. 1.

FIG. 2.

Inventor

Harry L. Hunt

By *Harold S. Sprecher*

Attorney

UNITED STATES PATENT OFFICE.

HARRY L. HUNT, OF BIGELOW, MISSOURI.

OIL CUP.

Application filed February 10, 1926. Serial No. 87,385.

This invention relates to new and useful improvements in oiling devices, and particularly to oil cups for attachment to moving machine parts.

5 One object of the invention is to provide a simple device of this character which can be manufactured at a comparatively low cost.

Another object is to provide a device of 10 this character which is durable and efficient in its operation, and which can be easily regulated whereby to discharge different amounts of lubricant.

Other objects and advantages will be apparent from the following description when taken in connection with the accompanying drawing.

In the drawing:

Figure 1 is a vertical view through an 20 oil cup made in accordance with the present invention, the discharge tube and cap thereof being shown in elevation.

Figure 2 is a vertical sectional view, but showing the discharge tube and cap in section.

Referring particularly to the accompanying drawing 10 represents the body of the oil cup which has the externally threaded attaching nipple 11, in its lower end, and the 30 removable threaded cap 12 on its upper end. Disposed vertically within the center of the cup, and having its lower end screwed into the interior of the said nipple, is a discharge tube 13. The upper end of the tube 35 13 is externally threaded to receive thereon the internally threaded cap 14. In the upper threaded end of the tube 13 there are formed the laterally directed openings 15, and in the cap 14 there are formed similarly shaped 40 and numbered openings 16, which are adapted to register with the openings 15, when said cap is rotated on the tube. In view

of the fact that the cap 14 moves longitudinally of the tube, when rotated, it is necessary to form the openings 15 and 16 slightly 45 elongated longitudinally of the tube, whereby to permit proper and complete registration when the cap is in a certain position, and whereby the maximum opening will be produced for escape of lubricant from the 50 cup into the discharge tube. The upper portion of the cap 14 is provided with the opposite flat faces 17, for engagement of a wrench, when it is necessary to rotate the cap for regulating the amount of lubricant 55 spilled through the said openings, as the cup moves with the machine part. As an additional means of rotating the cap 14, the upper end is provided with a transverse groove 18 for the reception of the end of 60 a screwdriver.

In the operation of the device, as the machine part moves the oil in the cup is sloshed around to such an extent that some of said oil will pass out through the registered openings 15 and 16, and through the discharge tube to the machine part. By rotating the cap 14 the openings can be regulated so that more or less oil will pass therethrough, thus providing for efficient lubrication of 70 the part.

What is claimed is:

An oil cup comprising an oil retaining receptacle, an outlet tube disposed vertically in the receptacle and having lateral openings 75 in its upper end, and a cylindrical cap mounted on said tube end having openings 80 in its flange cooperating with the openings of the tube for controlling the flow of lubricant through the cap and through said cooperating openings of the tube.

In testimony whereof, I affix my signature.

HARRY L. HUNT.
